LAMINATED BOWLING PIN
Jerald P. Hansen, R.F.D. 3, Atlantic, Iowa
Filed Oct. 12, 1961, Ser. No. 144,769
5 Claims. (Cl. 273—82)

This invention relates to a laminated bowling pin and has as its primary object the provision of an improved pin construction comprised of a plurality of layers or laminations of wood arranged about a central dowel in such manner that only the end grain of the wood is exposed at any point of the pin which can be impacted either by the ball or by striking the alley.

A further object of the invention is the provision of a bowling pin so constructed as to eliminate the slabbing off or the chipping of the wood construction along the grain lines, by virtue of this cross grain arrangement.

A still further object of the invention is the provision of a bowling pin of this character which by virtue of the above-mentioned end grain exposure of the wood is exceptionally long lasting and less subject to the normal difficulties of chipping or breaking encountered in conventionally constructed pins.

A still further object of the invention is the provision of a pin so constructed and arranged which will at the same time meet all of the requisite standards of all bowling associations.

An additional object of the invention is the provision of a central bore in the pin provided with a reinforcing insert comprising an aluminum or other suitable reinforcing tube.

Still other objects of the invention reside in the provision of a bowling pin which is exceptionally sturdy in construction, and which may be manufactured and assembled with a minimum of effort, difficulty, and cost.

Other objects will in part be obvious and in part be pointed out as the description of the invention proceeds and shown in the accompanying drawings wherein:

FIGURE 1 is an elevational view of a bowling pin constructed in accordance with the instant invention with certain concealed parts thereof being indicated in dotted lines.

FIGURE 2 is a sectional view taken substantially along the line 2—2 of FIG. 1 as viewed in the direction indicated by the arrows.

FIGURE 3 is a sectional view taken substantially along the line 3—3 of FIG. 1 as viewed in the direction indicated by the arrows.

FIGURE 4 is a sectional view taken substantially along the line 4—4 of FIG. 1 as viewed in the direction indicated by the arrows.

FIGURE 5 is a sectional view taken substantially along the line 5—5 of FIG. 1 as viewed in the direction indicated by the arrows.

FIGURE 6 is a sectional view taken substantially along the line 6—6 of FIG. 1 as viewed in the direction indicated by the arrows.

FIGURE 7 is a sectional view taken substantially along the line 7—7 of FIG. 1 as viewed in the direction indicated by the arrows.

FIGURE 8 is a sectional view taken substantially along the line 8—8 of FIG. 1 as viewed in the direction indicated by the arrows.

FIGURE 9 is a sectional view taken substantially along the line 9—9 of FIG. 1 as viewed in the direction indicated by the arrows.

FIGURE 10 is a sectional view taken substantially along the line 10—10 of FIG. 1 as viewed in the direction indicated by the arrows; and

FIGURE 11 is a schematic sectional view showing the assembly and graining of the component segments of the pin prior to finishing.

2

Similar reference characters refer to similar parts throughout the several views of the drawing.

Having reference now to the drawings in detail, the bowling pin of the instant invention is generally indicated at 20 and comprises a central substantially circular dowel 21 with the grain running longitudinally, that is, perpendicular to the level of the alley. The dowel or core 21 is provided with a longitudinal bore 22 in which is positioned a reinforcing tube 23 of aluminum or other desired material in accordance with the requirements for weight in the pin. The upper end of the tube 23 is closed by a suitable plug 24.

The lower end of the core or dowel 21 is inserted in a plastic cup 25 in the conventional manner as is customary with present day bowling pins. The longitudinal extension of the grain at the lower end of the core is important as to prevent the bottom from breaking off transversely. The strength of the wood supports the plastic ring or cup, the latter merely serves to maintain a true bottom.

In order to prevent the slab grain from slabbing or chipping off at the upper extremity of the head of the pin, there is provided a transverse bore 26 in which is fitted and glued a dowel 27 with the grain running longitudinally of the head of the pin or parallel to the level of the alley. The dowel 27 thus presents at the point of maximum thickness of the head, at the two points of slab grain which are always on opposite sides from each other when dowel 21 is turned from a single piece of wood, and in a direction transverse to the grain of the head an end grain portion, 30 which is highly resistant to the chipping off of slabs of the upper head or neck portion of the pin. As best shown in FIG. 3, the dowel 27 is inserted prior to the boring of the bore 22 and the insertion of the reinforcing tube 23.

It may here be pointed out that while both bore 22 and tube 23 are herein disclosed as of uniform diameter throughout, that the bore and consequently the tube, may be tapered from top to bottom, if desired.

The body of the pin is comprised of layers or laminations, each comprised of a plurality of sections of wood which are cut cross grain as shown in FIG. 11 so that all points of the pin which may be struck by a ball or strike against the alley, present end grain structure which is much more highly resistant to chipping or slabbing than the longitudinal grain of the center core. The layers are designated in FIGS. 1 and 2 from top to bottom as 30, 31, 32, 33, 34, and 35. There may obviously be as many of these layers as necessary or desirable, and each layer may be of any desired thickness or vertical height. The overall conformity with the standard bowling pin provides the essential criterion. In FIG. 5 taken through the center line of the layer 30 there are three sections 30a, 30b, and 30c, each of which is cut in such manner that the end grain as indicated extends transversely to the grain of the core 21 and is positioned to extend longitudinally to a direction of impact. As seen by the line 30d, the grain of the members 30a, 30b, and 30c is parallel to a line diagonal to the transverse grain of the core 21.

The layer or lamination 31 is shown in FIG. 6 and comprises three similar sections 31a, 31b, and 31c. In each instance the grain is cut in the same manner as that described in connection with FIG. 5 and the segments are offset relative to the position of the segments 30a, 30b, and 30c, the junctures of which are indicated by the lines 30a', 30b', and 30c' in FIG. 6. The grain along which the sections are cut is perpendicularly aligned. FIG. 7 discloses lamination 32 which in turn is comprised of segments 32a, 32b, and 32c which segments are secured together along the lines 32a', 32b', and 32c', these lines being in substantial alignment with the connecting lines 30a', 30b', and 30c', and offset from the lines 31a', 31b', and 31c' along which the sections 31a, 31b, and 31c are secured. The section 33 as shown in FIG. 8 is comprised of

sections 33a, 33b, and 33c glued together along the lines 33a', 33b', and 33c', cut oppositely to the axis as in the foregoing segments. Similarly, section 34 is comprised of three sections 34a, 34b, and 34c, the alignment of which is offset relative to the lines 33a', 33b', and 33c'. The lowermost lamination 35 is also comprised of sections 35a, 35b, and 35c which are again offset relative to the connecting lines 34a', 34b', and 34c' of FIG. 9. The thickness radially of each of the sections is in accordance with the dimensioning of a conventional bowling pin, and is formed on a lathe after the initial assembly of the several blocks about a common core 36 as shown in FIG. 11, each of blocks 36a, 36b, and 36c which may correspond to any of the layers of laminations above described, having its end grain facing outwardly from the center of a central core member. After the blocks have been initially formed and glued together along the diagonal lines as indicated and previously discussed, drilled out along the center to the size of the core 21, assembled over core 21 and similarly glued to the dowel or core 21, the pin is turned into final shape. The insertion of the dowel 27, the formation of the bore 22, the insertion of the reinforcing tube 23 and the final assembly of the plastic cup 25 are all, of course, steps taken after the initial formation and turning of the pin after assembly of its component blocks.

After the formation and assembly of the pin the customary layer or layers of lacquer 37 are provided to give the pin the required exterior finish, such lacquer completely covering the body, the neck, and the head of the pin.

From the foregoing it will now be seen that there is herein provided an improved laminated bowling pin which accomplishes all the objects of this invention, and others, including many advantages of great practical utility and commercial importance.

As many embodiments may be made of this inventive concept, and as many modifications may be made in the embodiment hereinbefore shown and described, it is to be understood that all matter herein is to be interpreted merely as illustrative, and not in a limiting sense.

I claim:

1. A bowling pin having a head portion, a neck portion, a body portion and a base portion and being adapted

to stand in vertically disposed relationship to a horizontally extending bowling alley, said pin comprising a central core of wood having the grain thereof extending substantially vertically when said pin is standing, a plurality of laminae surrounding said core over at least the body portion of said pin and secured to each other at substantially horizontally extending bonding junctures, each of said laminae including a plurality of segments of wood secured to each other at substantially vertically extending bonding junctures, the end grain of each of said segments extending substantially horizontally and being substantially radially disposed with respect to said core.

2. A structure in accordance with claim 1 wherein said vertically extending bonding junctures of adjacent laminae are radially offset with respect to each other.

3. A structure in accordance with claim 1 wherein each of said laminae includes three substantially equal segments.

4. A structure in accordance with claim 1 wherein the head portion of said pin comprises the top portion of said core, a horizontally extending transverse bore defined through said head portion, and a plug of wood secured in said transverse bore having the grain thereof extending substantially horizontally and substantially longitudinally of said transverse bore.

5. A structure in accordance with claim 4 wherein a vertically extending longitudinal bore is defined substantially centrally through said core and transversely through said plug, and a reinforcing member is secured in said longitudinal bore.
